UNITED STATES PATENT OFFICE

2,066,061

SLIDER FOR SLIDE FASTENERS

Gideon Sundback, Meadville, Pa., assignor to
Hookless Fastener Company, Meadville, Pa., a
corporation of Pennsylvania

Application October 31, 1933, Serial No. 696,055

6 Claims. (Cl. 24—205)

My invention relates to sliders for slide fasteners. The expression "slide fastener" as used in the art, refers to a fastening device having cooperating rows of small closely spaced fastener elements secured to the opposite edges of the gap to be closed, and having a slider mounted on the elements for quickly engaging and disengaging them as it moves from one end to the other of the fastener.

10 My invention aims particularly to improve the slider construction in respect to the pull device which is adapted to be grasped by the fingers in operation of the slider. In prior constructions, lugs, rigid loops or rivet heads extended upwardly 15 from the slider body and in many cases, such constructions were bendable when stepped upon or when passed through laundering machinery. Such devices are always unsightly because they present a bulge or projection which is often a 20 serious objection.

According to my invention a flexible member is attached to the slider body and there are no lugs or other projections to break the flat upper surface of the slider. Such flexible member is foldable so that it can be pushed down against the 25 slider without injuring it.

The illustrated embodiment of my invention is intended especially for use with non-metallic sliders. In sliders of non-metallic material, the old 30 constructions have even more serious disadvantages because such lugs or loops would have to be larger in order to possess the necessary strength.

In the accompanying drawing, I have shown 35 for purposes of illustration some embodiments which my invention may assume in practice. In this drawing:

Fig. 1 is a general face view of a slide fastener with a slider made in accordance with my invention;

Fig. 2 is a perspective view of the slider shown in Fig. 1;

Figs. 3 and 4 are perspective views showing the modified constructions; and

Fig. 5 is a side view of the slider shown in Fig. 2.

The slide fastener illustrated comprises cooperating rows of fastener elements 7 attached to the beaded edges 8 of fabric tapes 9. The fastener is applied in any article desired to be fastened by stitching or otherwise securing the tapes to the edges of the article.

The slider consists of a body member 10 having an interior Y-shaped channel 11 for guiding the 55 fastener elements in and out of intermeshing

relation. The slider body has upper and lower wings with flat surfaces. Such a slider may be formed from non-metallic material, such as pyroxylin, by cutting out the Y-shaped channel from solid block or by milling the slider in halves and 5 sticking them together.

In Fig. 2 a fabric strip such as the cloth ribbon 12 is attached at its ends to the opposite ends of the slider and extends over the upper flat surface. Preferably the ends of the strip are adhesively 10 secured to the slider. This may be accomplished by the use of cement, glue or the like; or by bringing the strip and non-metallic material of the slider into contact with each other while the material of the slider is in a softened state. This softening 15 may be produced by heat, solvents or other means. Preferably also the ends of the ribbon are embedded in recesses 13 in the slider. A pull tab 14 of any desired shape, is slidably mounted on the ribbon 12 and forms a convenient device for 20 actuating the slider in either direction. When the slider is pulled downwardly the pull tab will slide to the forward end of the ribbon, and when the slider is pulled upwardly as viewed in Fig. 1, the pull tab will slide to the upper end. 25

In Figs. 3 and 4 the ribbons are secured directly to the top surface of the slider. In Fig. 3 the ribbon 15 itself forms the pull tab which is adapted to be grasped by the fingers. It is preferably secured at one end by embedding in recess 16 30 and adhesively securing the same in a manner similar to that above described.

In Fig. 4 the ribbon is secured at both ends 17 by the use of solvent or any other adhesive means. In this construction, a loop 18 is formed so that 35 a finger can be placed through the loop for operating the slider.

In all of these forms it will be observed that the pull device is foldable into substantially flat condition against the flat upper surface of the 40 slider. It can not be injured by stepping on it nor by passing through laundering machines or presses. Furthermore, there is no unsightly bulge or projection to mar the appearance of articles in which the fastener is placed. 45

While I have shown and described in this application several embodiments which my invention may assume in practice, it will be understood that these embodiments are merely for the purposes of illustration and description, and that 50 various other forms may be devised within the scope of my invention as set forth in the appended claims.

What I claim as my invention is:

1. A slider for slide fasteners comprising a 55

non-metallic channeled body member having smooth outer surfaces, and a flexible fabric strip adhesively secured to the said body member and constructed so as to lie flat against an outer surface of said body member or be lifted away from such surface when used for operating the slider.

2. A slider for slide fasteners comprising a channeled body member having an upper surface and a flexible flat fabric strip secured to said body member and adapted to be folded flat against said upper surface, said upper surface being entirely flat except for the flexible fabric strip.

3. A slider for slide fasteners comprising a channeled body member made of non-metallic material, and a flexible fabric strip adhesively secured to said channeled body member.

4. A slider for slide fasteners comprising a channeled body member having a flat upper sur-

face, a fabric strip secured to opposite ends of said slider body and extending over said flat surface, a pull tab attached to said fabric strip and slideable from one end to the other of the slider.

5. A slider for slide fasteners comprising a channeled body member of non-metallic plastic material, a flexible pull member having at least one of its ends embedded in said body member for securing the same thereto.

6. A slider for slide fasteners comprising a channeled body member of plastic material and having a flat upper surface, and a cloth ribbon having its ends secured to said flat upper surface and extending upwardly therefrom in the form of a loop functioning as a pull member, and being foldable to be flat against said upper surface.

GIDEON SUNDBACK.
